UNITED STATES PATENT OFFICE

GERTRUDE F. WATERS AND GILBERT A. WATERS, OF SHARON, CONNECTICUT

HAIR WAVING COMB

Application filed September 22, 1931. Serial No. 564,308.

This invention relates to a device for waving hair upon the head, and comprises two or more combs of suitable shape and size, which are arranged one above the other with their teeth pointing upward and having their backs joined together by bars, which are pivoted to the upper comb in a semi-rigid manner, and to the other comb in such a manner that the lower comb may have movement in several directions to conform to the shape of the head.

The object of the invention is to provide an article of this kind that shall be simple, durable and efficient, easily applied and removed.

Another object being to provide an article of this class that shall retain its position in the hair in a positive manner, and produce a satisfactory wave to the hair.

With these and other objects in view, our invention consists in certain novel construction and combination of parts as will be hereinafter described and claimed, and fully illustrated in the accompanying drawing, which forms a part hereof and in which like figures of reference refer to corresponding parts in all of the views, but it is understood that slight changes may be made without departing from the spirit of the invention.

In the drawing:—

Figure 1 shows a front elevation of our device in position for being inserted into the hair.

Figure 2 shows a similar view, but with the combs in the position they assume after being inserted into the hair and in position for holding the wave.

Figure 3 is a cross sectional view, showing the relative position of the combs and hair when the combs are in a set position.

Figure 4 shows a cross sectional view of the combs as shown in Figure 1.

Referring to the drawing:—

The device comprises, two or more combs 10 and 11, which may be straight or curved

as desired or of any suitable shape and size and which are formed with the backs or ribs 12 and 13.

These combs 10 and 11 are secured together in an adjustable manner by the bars 14; the upper ends of which are pivoted to the back 12 of the comb 10 by the rivets 15 in a frictional manner; that is, that the position of the comb 10 with respect to the bars 14 may be retained in any position desired by the user.

The lower ends of the bars 14 are secured to the back 13 of the comb 11 in a perfectly freely movable manner by the rings 16 which are passed through the holes 17 and 18 which are formed in said bars 14 and the comb back 13.

In this manner it will be seen that the lower comb 11 may not only be moved endwise with respect to the upper comb 10, but may also be swung inward or outward in such a manner that both of the combs will conform to the shape of the head and lie close thereto, as shown in Figure 3.

In the operation of the device, it will be noted that the combs 10 and 11 are inserted into the hair from the bottom or lower part of the head upwards, and after being properly inserted one comb is moved sidewise with respect to the other, thus producing a wave in the hair between said combs.

The hair is then sprayed with some suitable solution that when dry will retain the wave which has been placed therein by the combs.

Having thus described our invention, what we claim as new and desire to procure by Letters Patent, is—

1. A hair waving device comprising a plurality of combs, and link means inter-connecting said combs, the connection between one end of said link means and one of said combs consisting of a frictionally retarded pivot and the connection between the other end

of said link means and the other of said combs comprising a freely movable pivot.

2. A hair waving device comprising a plurality of combs, link means having pivot means engageable with one of said combs, and additional link means having freely movable pivots inter-connecting said first named link means and the other of said combs.

In testimony whereof we affix our signatures.

10   **GERTRUDE F. WATERS.**
                      GILBERT A. WATERS.
